Primary Examiner — Cynthia Ramirez*Assistant Examiner* — Xavier Marti-Santos(74) *Attorney, Agent, or Firm* — Adams Law Office;
 Sharon Adams**CLAIM**

The ornamental design for a frame, as shown and described.

DESCRIPTION

FIG. 1 is a front elevational view of a frame showing my new design;

FIG. 2 is a rear elevational view thereof;

FIG. 3 is front elevational view thereof;

FIG. 4 is rear elevational view thereof;

FIG. 5 is side elevational view thereof;

FIG. 6 is a top plan view thereof; and,

FIG. 7 is a bottom plan view thereof.

The broken lines in FIGS. 1 and 2 are to show environment and form no part of the claimed design. The additional broken lines shown in FIGS. 2-7 are to show portions of the frame, which form no part of the claimed design.

1 Claim, 6 Drawing Sheets(56)
